L. M. REED

POWER HANDSAW

Filed March 30, 1925

Patented Jan. 12, 1926.

1,569,301

UNITED STATES PATENT OFFICE.

LEONARD M. REED, OF DEXTER, IOWA.

POWER HANDSAW.

Application filed March 30, 1925. Serial No. 19,239.

To all whom it may concern:

Be it known that I, LEONARD M. REED, a citizen of the United States of America, and resident of Dexter, Dallas County, Iowa, 5 have invented a new and useful Power Handsaw, of which the following is a specification.

The object of this invention is to provide an improved motor-operated reciprocating 10 saw adapted for hand use.

A further object of this invention is to provide a motor-operated hand saw which is self-contained, the motor being enclosed in a housing which also contains the gearing 15 for causing the reciprocating movement.

A further object of this invention is to provide an improved motor-operated hand saw which is of simple and relatively inexpensive construction but efficient in use.

20 A further object of this invention is to facilitate the operator's control over the saw and the driving means.

A further object of this invention is to provide a motor-driven saw in which the 25 blade may readily be detached and substituted by another.

With these and other objects in view, my invention consists in the construction, arrangement and combination of elements 30 hereinafter set forth, pointed out in the claims and illustrated by the accompanying drawing, in which—

Figure 1 is a side view of my improved device. Figure 2 is an enlarged cross-section taken on the line 2—2 of Figure 1. Figures 3 and 4 are longitudinal sections on the lines 3—3 and 4—4 respectively of Figure 2. Figure 5 is a detail section on the line 5—5 of Figure 4, and Figure 6 is a detail section on the line 6—6 of Figure 3.

40 In the construction of the device as shown the numeral 10 designates a cylindrical housing, the upper end of which is normally closed by a screw-threaded dome-shaped cap.

45 Attached to the outside of the housing 10 is a handle 12 by which the device may be held and manipulated. A carriage 13 is arranged transversely within the housing 10 and is adapted for reciprocation longitudinally thereof, being formed at its ends with tongues 14 projecting within grooves 15 formed in opposite portions of the walls of said housing and arranged lengthwise thereof. Stops 16 are provided at the ends of 50 the grooves or tracks 15, and cushioning springs 17 are mounted on said stops to

cushion the carriage 13 at each end of its range of travel. A saw blade such as 18 is attached at its base to the carriage 13 as by means of bolts 19, the major portion of 60 said blade projecting out through the open or partially open lower end of the housing. A number of blades may be provided for use with a given device, which blades may be of different character if desired, and access is had to the fastening bolts through an opening in the side of the housing, normally closed by a door 20.

A boxing 21 is arranged for reciprocation on the carriage 13, being guided in a slot or 70 opening 22 formed lengthwise of said carriage. Mounted on and carried by the boxing 21 is an electric motor 23, the shaft of which is connected by sprocket gearing 24 to a countershaft 25 journaled in the boxing 21 75 and extending diametrically of the housing, at right angles to the carriage 13. Endless racks 26, 27 are arranged longitudinally of and at opposite sides of the interior of the housing 10, said racks being of substantially 80 elliptical form and having outwardly directed teeth. Elliptical grooves or tracks 28 are formed in the walls of the housing adjacent and in embracing relation to the racks 26, 27, and the ends of the countershaft 25 project within and are guided by said grooves or tracks. Pinions 29, 30 are fixed to end portions of the countershaft 25 and are in mesh with and adapted to travel on the racks 26, 27 respectively.

90 The motor 23 is supplied with current by conductors 31, 32 in circuit with any suitable source of electrical energy, and if desired a switch 33 may be located in said circuit and a convenient place for said switch is on the handle 12 as shown, where it may be manipulated by the operator without moving his hand away from the handle, or held in closed position by one finger while the hand is gripping the handle.

100 In practical use the saw is held in the usual way and when the switch is closed the motor is operated and drives the sprocket gearing 24 and countershaft 25, thus rotating the pinions 29, 30 and causing them to 105 travel on the racks 26 and 27 respectively. This travel causes a rectilinear reciprocation of the carriage 13 in the housing, guided on the tracks 14, and carrying with it the blade 18 which is used in the sawing 110 operation, under the guide and control of the operator. The pinions pass from one

long side to the other of the racks at their rounded ends, and the long sides of said racks are as close together as practicable so that little transverse movement is required in passing from one side to the other. This transverse movement is permitted by the sliding movement of the boxing 21 in the track or opening 22 of the carriage, and such movement may be cushioned by 5 springs 34, 35 at the ends. The motor 23 of course travels with the boxing 21 in its transverse movements, which in turn travels with the carriage in its longitudinal movements, and the conductors 31, 32 are 10 of such length and flexibility as not to interfere with such travel.

I claim as my invention—

1. A power-driven hand saw, comprising a casing, a carriage arranged for rectilinear reciprocation therein, a saw blade fixed to said carriage and having its major portion projecting therefrom, a motor on and adapted for reciprocation with said carriage, and means connected with said motor for causing said carriage to reciprocate in said casing.

2. A power-driven hand saw, comprising a casing, a carriage arranged for rectilinear reciprocation therein, a saw blade fixed to said carriage and having its major portion projecting from said casing, a motor on and adapted for reciprocation with said carriage, means for cushioning said carriage at the ends of the range of movement, and 30 gearing mechanism operated from said motor to cause said carriage to reciprocate in said casing.

3. A power-driven hand saw, comprising a casing, a carriage arranged for reciprocation longitudinally thereof, a saw blade fixed to said carriage and having its major portion projecting from said casing, a rack carried by the wall of said casing, a motor on and adapted for reciprocation with said carriage, a countershaft arranged for rotation, and connected with said carriage, a 40 pinion on said countershaft in mesh with said rack and adapted to travel thereon, and gearing operatively connecting said motor to said countershaft.

4. A power-driven hand saw, comprising

a casing, an endless rack of elliptical form carried by the wall thereof and extending longitudinally thereof, a carriage arranged for reciprocation in said casing, a boxing arranged for limited reciprocation on said carriage transversely of said casing, a motor carried by said boxing, a countershaft journaled in said boxing, gearing mechanism between said motor and countershaft, a pinion 50 on said countershaft meshing with and adapted for travel on said rack, and a saw blade attached to said carriage and having its major portion extending outside of said casing.

5. A power-driven hand saw, comprising a casing, an endless rack of substantially elliptical form carried by and longitudinally of the wall of the casing, longitudinal guides in the walls of said casing, a carriage arranged for travel in said guides, a boxing arranged for limited reciprocation on said carriage transversely of said casing, a motor carried by said boxing, a countershaft journaled in said boxing, sprocket 70 gearing operatively connecting the motor shaft to said countershaft, a pinion on said countershaft meshing with and adapted for travel on said elliptical rack, and a saw blade detachably connected with said carriage.

6. A power-driven hand saw, comprising a casing, an endless rack of substantially elliptical form arranged longitudinally of the wall of the casing, a carriage arranged 85 for travel longitudinally of said casing, a boxing arranged for limited reciprocation on said carriage transversely of the casing, means for cushioning said boxing at the ends of its range of movement, a motor carried by said boxing, a countershaft journaled in said boxing, gearing operatively connecting the motor shaft to said countershaft, a pinion on said countershaft meshing with and adapted for travel on said 90 elliptical rack, and a saw blade secured to said carriage.

Signed at Dexter, in the county of Dallas and State of Iowa, this 28th day of February, 1925.

LEONARD M. REED.
